SKI-TOW APPARATUS

Theodore C. Cooke, Swampscott, Mass.

Application December 23, 1936, Serial No. 117,327

9 Claims. (Cl. 104—202)

This invention relates to improved ski-tow apparatus, and has for its object to provide a ski-tow whereby ski-riders may be expeditiously and safely pulled up slopes.

5 Heretofore various sorts of ski-tows that have been used have involved a primary mover driving a tow-rope extending up a slope with hold-on devices permanently affixed to the tow-rope at intervals, but most ski-tows heretofore have required that the ski-riders hold on to the rope simply by their hands and such ski-tows have not proved very satisfactory, particularly when the tow-rope is slippery. By means of this invention, however, an effective and convenient 15 hold-on device is provided which, in combination with an ordinary fibrous tow-rope, provides under all conditions an effective gripping means so that ski-riders can quickly and readily apply or remove the same as required and be pulled up slopes preparatory to sliding down. The removal of the hold-on device is so easily accomplished as to render safe its use even by the young, and if necessary, for any reason, the hold-on device can simply be released and no 20 harm can come either to the user or to the apparatus.

The present invention involves a prime mover and pulley means arranged and adapted to tension and drive a tow-rope, together with a novel 25 form of hold-on device as will be hereinafter more fully described.

In the drawing:

Fig. 1 illustrates a perspective view of the complete apparatus in use towing ski-riders up a 30 slope;

Fig. 2 shows a perspective view of a ski hold-on device in place and gripping a tensioned tow-rope;

Fig. 3 is an enlarged perspective view illustrating the hold-on device without the tow-rope;

Fig. 4 is a side elevation of the hold-on device showing a tow-rope in cross-section.

Referring to the drawing in which like numerals represent like parts:

The preferred form of apparatus involves a prime mover 2 (here shown as an electric motor though any suitable one may be substituted) driving through gears 4 a shaft 6 carrying and 45 driving a tow-rope 7 by means of a driving drum or pulley 8, about which the rope is wrapped two or three turns. Said pulley 8 together with additional pulleys 10, 12 and 14 complete the pulleys for tensioning the two long flights of 50 driven tow-rope 7, the lower flight of which is

the ascending or working flight and the upper or return flight down the slope to the bottom station. The hold-on devices, generally designated 16, are employed by ski-holders 20 to firmly grip the tow-rope 7 and enable the ski-riders to be drawn up the slope at the rate of movement of the ascending flight of tow-rope 7.

The hold-on devices include a handle portion 22 affixed to a shank portion 24 which connects two oppositely facing hook-members 26 which, in the preferred form as shown, extend from opposite ends of the shank or connecting portion and at substantially right angles to the axis of said shank or connecting portion 24, being oriented at approximately 90° about the 15 axis thereof as best shown in Fig. 4. In order to provide for ready application to and removal from the tow-rope 7, the hooks are spaced apart a distance somewhat greater than the diameter of the tow-rope 7. The preferred form of hook 20 as shown involves a right-angularly bent hook portion 26, or at least an angle sufficiently sharp so that the tow-rope 7, when nipped, does not extend completely into the bend of the preferred form hook as shown, that is, the tow-rope does 25 not "bottom" in the hook but, instead, contacts at two circumferentially separated areas. In this way, the bite of each hook 26 appears to be more effective, particularly when the user places the same on the tow-rope by first putting the handle 30 more or less aligned with the tow-rope, thus bringing the plane of each hook approximately parallel to the axis of the tow-rope, and then, by an arcuate movement of the handle 22 moving the handle to a position transversely of the tow-rope in a direction in general opposite to the axis of the tow-rope so that one hook pushes into the tensioned tow-rope and the other pulls to kink 35 and nip on opposite sides a short length of the tensioned tow-rope between said hook-members, 40 thereby firmly gripping the same so as to enable a ski-rider to easily hold on and ride up the slope. Upon approaching the upper end of the ski-tow, each ski-rider 20, by a quick forward movement of the handle, releases it from the rope and descends the slope, usually carrying the hold-on 45 device in his pocket or at his belt where it may be conveniently carried.

In the preferred form of device as shown, the hollow handle is somewhat curved so that despite 50 variations in the tension of the rope and/or pull of the rider with consequent variations in the angular relation of the handle, the rider will, as a practical matter, always have some part of the handle normal to the axis of the flight of the 55

tow-rope and hence also normal to his pull. This avoids any tendency for the rider's hands to slip relative to the handle and makes it easier for him to hold on to.

5 Having described my invention, what I wish to claim and secure by Letters Patent is:

1. A ski-tow apparatus comprising a power-driven endless tow-rope and hold-on devices therefor, each of said devices having an elongated handle and a shank having rigid angular hook-members projecting forwardly from the ends thereof, said members adapted to be placed in removable engagement with said tow-rope at opposite sides thereof and to bend the tow-rope whereby to lock the handle thereto when the shank portion is held in resistance to the motion of the tow-rope.

2. A ski-tow apparatus comprising a power-driven endless tow-rope and hold-on devices therefor, each of said devices having an elongated handle and a shank having rigid angular hook-members projecting at substantially right angles forwardly from the ends thereof and at substantially right angles to each other, said members adapted to be placed in removable engagement with said tow-rope at opposite sides thereof and to bend the tow-rope whereby to lock the handle thereto when the shank portion is held in resistance to the motion of the tow-rope.

3. In ski-tow apparatus, in combination, an endless tow-rope, a prime mover and pulley means arranged and adapted to tension and to drive said tow-rope to provide continuous movement and return thereof, a series of ski-tow hold-on devices adapted to be removably held on the ascending flight of said tow-rope by means of pressure applied by ski-riders in a direction generally opposite to the movement of said rope, each device comprising oppositely facing members with each said member providing a tow-rope contacting portion and encompassing a substantial portion of the circumference of the rope so as together to circumferentially sufficiently surround the rope on opposite sides thereof to prevent accidental escape by a relative radial movement thereof, a connecting portion rigidly holding said members in fixed relative position along a tow-rope extending therebetween and spaced apart a distance at least equal to the diameter of the tow-rope, and a relatively long handle portion extending sidewise from said connecting portion whereby pressure applied transversely of said handle portion kinks and nips on opposite sides the rope between said members and thereby firmly grips the same.

4. As a new article of manufacture, a ski-tow hold-on device having, in combination, an elongated handle, a shank portion having two rigid angular hook-members projecting forwardly from an end thereof, said members adapted to be removably hooked about opposite sides of a ski-tow rope and to be forced in opposite directions against said tow-rope by lateral pressure applied to said handle, whereby to bend said tow-rope and lock said handle thereto.

5. As a new article of manufacture, a ski-tow hold-on device having, in combination, an elongated handle, a shank portion having two rigid, spaced, oppositely-disposed hooks projecting forwardly therefrom for gripping a ski-tow rope, said hooks being adapted to be loosely fitted about opposite sides of a ski-tow rope when the shank portion is held at right angles to said tow-rope,

and to be forced in opposite directions into gripping engagement with said tow-rope by an arcuate movement of the shank portion.

6. A ski-tow hold-on device comprising oppositely facing members each providing a tow-rope contacting portion and encompassing a substantial portion of the circumference of the rope so as together to circumferentially sufficiently surround the rope on opposite sides thereof to prevent accidental escape by a relative radial movement thereof, a connecting portion rigidly holding said members in fixed relative position along a tow-rope extending therebetween and spaced apart a distance at least equal to the diameter of the tow-rope, and a relatively long handle portion extending sidewise from said connecting portion whereby pressure applied transversely of said handle portion kinks and nips on opposite sides the tensioned rope between said members and thereby firmly grips the same.

7. A ski-tow hold-on device comprising oppositely facing hook-members each providing a tow-rope contacting portion and encompassing a substantial portion of the circumference of the rope so as together to circumferentially sufficiently surround the rope to prevent accidental escape by a relative radial movement thereof, a connecting portion rigidly holding said members in fixed relative position along a tow-rope extending therebetween and spaced apart a distance at least equal to the diameter of the tow-rope, and a relatively long handle portion extending sidewise from said contacting portion whereby pressure applied transversely of said handle portion nips and angularly displaces said members to push one member and pull the other member so as to engage and nip a tensioned rope extending therebetween and minimize movement of said device along said rope.

8. A ski-tow hold-on device comprising two oppositely facing angularly-formed members each of which provides a reentrant angular, discontinuous rope-gripping means with each member adapted to encompass not to exceed half the circumference of a tow-rope and with each member contacting two circumferentially separated portions, a connecting portion rigidly holding said members in fixed relative position to provide an unobstructed space therebetween and with said members for the reception of a tow-rope, and a relatively long handle portion extending sidewise from said connecting portion whereby pressure applied transversely of said handle portion nips the rope between said bent members to prevent the escape of and grip a tensioned rope extending therebetween.

9. A ski-tow hold-on device comprising two oppositely facing members each providing a tow-rope contacting portion and encompassing approximately half of the circumference of the rope so as together to surround a tow-rope and prevent the accidental escape thereof, a connecting portion integral with and rigidly holding said members in fixed relative position to provide an unobstructed space therebetween for the reception of a tow-rope, and a relatively long handle portion extending sidewise from said connecting portion whereby pressure applied transversely of said handle portion nips the rope between said bent members to grip a tensioned rope extending therebetween and oppositely applied pressure frees the rope.

THEODORE C. COOKE.
